UNITED STATES PATENT OFFICE.

HARRY R. DECKER, OF HOUSTON, TEXAS.

OIL AND WATER WELL STRAINER.

No. 895,733.

Specification of Letters Patent.

Patented Aug. 11, 1908.

Application filed August 1, 1906. Serial No. 328,748.

To all whom it may concern:

Be it known that I, HARRY R. DECKER, a citizen of the United States, residing at Houston, in the county of Harris and State 5 of Texas, have invented certain new and useful Improvements in Oil and Water Well Strainers, of which the following is a specification.

My invention relates to strainers for use in 10 wells, and consists of a tube having perforations therein with their inner portions smaller in diameter than their outer portions and forming shoulders in said perforations, the 15 walls of the outer portions of the perforations being beveled inwardly to the shoulders to receive a slotted or perforated plate that forms the strainer to exclude sand and other foreign substances but permitting fluids such as oil or water to pass therethrough and into 20 the tube to be conveyed to the top of the well.

My invention contemplates riveting the plate referred to securely in the recessed portion of the perforation, by which manner of 25 fastening it becomes substantially a part of the strainer tube and materially strengthens it where it is weak, at the perforations.

The construction and advantages of my 30 improved strainer will be described in detail hereinafter and illustrated in the accompanying drawings, in which—

Figure 1 is a view of a fragment of a strainer tube partly broken away and in section showing my improvements combined 35 therewith, Fig. 2, a detail view of one of the disks, Fig. 3, a cross section of the disk shown in Fig. 2, Fig. 4, a view of a modified form of disk, and Fig. 5, a cross section of the disk shown in Fig. 4.

40 In the drawings similar referenced characters indicate corresponding parts throughout the several views.

A indicates a tube or pipe in which is 45 drilled a number of holes B having their outer portions formed larger in diameter than the inner portions said outer portions being indicated at b and are adapted to receive strainer disks C which seat against shoulders b' formed by the differences in the 50 diameter of the inner and outer portions of the holes, and are held in position by upsetting the metal of the pipe surrounding the holes B, as shown at D, so as to clenched the disks C in position.

55 In the disk shown in Figs. 1, 2 and 3, paral-

lel slots E are provided therein having beveled sides with the narrowest opening of the slot towards the exterior of the strainer tube, while in the form shown in Figs. 4 and 5 round holes F are made in the disk, the holes 60 having beveled sides with the smaller ends of the holes towards the exterior of the strainer as in the construction of strainer having slots. The beveled holes and slots prevent the obstruction thereof by particles of sand 65 or clay that might be carried therethrough by the fluid.

Among the advantages of this form of strainer are that the outer surface of the strainer tube has no depressions therein to 70 become clogged by accumulating mud and sand, which is the case in strainers in which the strainer surfaces set back from the outer surface of the tube, while the depression that is formed at the inner ends of the holes B provide for the reception of a plug of cement or 75 other plastic material G should it be desired to convert the strainer tube into a well tube for further boring after the exhaustion of a stratum of oil or water. By setting the 80 strainer disk into a depression such as shown at b an enlarged strainer surface in proportion to the diameter of the hole B in the tube is secured and, as the disks C are securely held in position and fit snugly the recesses in 85 the tube, because of the beveled walls of the holes in the tube and the beveled sides of the disk, the tube is strengthened where needed at the places where perforated. It will be 90 apparent also that the corresponding beveled sides of the disks and their retaining holes insure the disks fitting closely in the holes so that a fluid tight fit is insured and the oil or water can not enter the strainer except 95 through the strainer openings.

Having thus described my invention what I claim is—

1. In an oil and water well strainer, a tube 100 having holes therein having their outer portions larger in diameter than their inner portions, and perforated disks seated in the outer portions of said holes, said disks being held in position by upsetting the metal of the tube to clenched them, substantially as shown and described.

2. In an oil and water well strainer, a tube 105 having holes therein having their outer portions larger in diameter than their inner portions, and slotted disks seated in the outer portions of said holes, said disks being held in 110

position by upsetting the metal of the tube to clench them, substantially as shown and described.

3. In an oil and water well strainer, a tube having holes therein having their outer portions larger in diameter than their inner portions, and perforated disks seated in the outer portions of said holes, said disks being held in position by upsetting the metal of the tube to clench them, the perforations in said disks having beveled sides with the narrowest portions towards the exterior surface of the tube, substantially as shown and described.

15 4. In an oil and water well strainer, a tube having holes therein having their outer portions larger in diameter than their inner portions, and slotted disks seated in the outer portions of said holes, said disks being held in position by upsetting the metal of the tube to clench them, the slots in said disks having beveled sides with the narrowest portions towards the exterior surface of the tube, substantially as shown and described.

25 5. In an oil and water well strainer, a tube having holes therein with beveled walls, and perforated disks having beveled sides seated in said holes and secured therein by upsetting the metal of the tube to clench them, substantially as shown and described.

30 6. In an oil and water well strainer, a tube having holes therein with beveled walls, and slotted disks having beveled sides seated in

said holes and secured therein by upsetting the metal of the tube to clench them, substantially as shown and described.

7. In an oil and water well strainer, a tube having holes therein with their outer portions larger in diameter than their inner portions, said outer portions having outwardly flaring walls, and perforated disks having beveled sides to fit snugly said flaring walls and secured therein by upsetting the metal of the tube to clench them, the perforations in said disks having beveled sides with the narrowest portions towards the exterior surface of the tube, substantially as shown and described.

8. In an oil and water well strainer, a tube having holes therein with their outer portions larger in diameter than their inner portions, said outer portions having outwardly flaring walls and slotted disks having beveled sides to fit snugly said flaring walls and secured therein by upsetting the metal of the tube to clench them, the slots in said disks having beveled sides with the narrowest portions towards the exterior surface of the tube, substantially as shown and described.

In testimony whereof I hereto affix my signature in the presence of two witnesses.

HARRY R. DECKER.
